UNITED STATES PATENT OFFICE.

JOHN D. CANTONI, OF NAPA, CALIFORNIA.

DRYING APPARATUS.

Application filed November 3, 1925. Serial No. 66,449.

This invention relates to an apparatus for drying fruits and vegetables, and its object is to produce a drier which will be so formed as to deliver the hot air to the fruit or vegetables at a time when the materials can best withstand the greatest heat and to lead up to and away from that particular stage in such a way as to produce the best quality of dried materials.

10 It will be understood by those skilled in the art that in the earliest stages of the drying, the temperature must not be too high, but that during an intermediate stage of the drying, the temperature can be considerably

15 higher without injuring the fruits or vegetables, but that during the latter stages of the drying, the temperature must be again somewhat lower, so that in the present instance, the drying chambers are so arranged

20 as to have the fruit move from the cooler end of the drier to the hotter end, and then to have the cars containing the trays turned around and moved in another channel away from the hottest part of the drier to the

25 cooler portion thereof until the end of the treatment.

A further object of the invention is to provide means whereby the movement of the cars along the drying tracks and on to the turn table and out of the drier, will be accomplished by the mere operation of a power driven cable.

Another object of the invention is to provide means whereby the furnace can be located outside of the main walls of the drier while the smoke flues are arranged inside the upper portion of the drier in such a way as to prevent the escape of any smoke in the two drying chambers, and provision is also made for permitting the escape from the drying chamber of a certain amount of air to insure the removal from the drier of moisture carried by the materials being treated, freshly heated air being taken into the drier from the space around the furnace.

An embodiment of the invention is shown in the accompanying drawings in which the same reference numeral is applied to the same portion throughout the several figures of the drawings and of which there may be modifications.

Figure 1 is a vertical sectional view of the complete drier.

Figure 2 is a plan view of the complete drier, the plane of section being taken to show the cars for the trays.

Figure 3 is a plan view of the drier in section showing the upper chamber of the drier and illustrating the portion of the smoke flues.

Figure 4 is a plan view of the mechanism for driving the cars in to the drier and out of it, and for turning the cars around.

Figure 5 is a side elevation of the driving mechanism.

Figure 6 is a side elevation of the hook for pulling the cars off the turn table and pushing the entire line of cars out of the drier, the movement taking place one car at a time.

Figure 7 is a side elevation of the hook for pulling the cars into the drier and on to the turntable.

This drier is intended to be of a size to take a series of cars illustrated at 1, which are supported by four wheels indicated at 2 and 3, and upon which are placed stacks of trays 4, the number of cars being dependent upon the length of the tunnel used and the capacity of the drier desired. The cars run upon two sets of tracks 5 and 6 and they are turned around inside the drier upon a turn table 7 in a manner later to be described. The walls 8, 9, 10 form a somewhat rectangular structure provided with four doors 11, 12, 13 and 14 at one end of the structure, while the drying tunnels are separated from each other by a partition 15, which extends to the turn table and the tunnels are covered over by the horizontal partition 16, while above that is the outside cover, or roof 17. The outside walls of the drier are made sufficiently thick to prevent the loss of undue heat, and at one side of the enclosure near the turn table is placed the furnace 18. The furnace is enclosed by a separate wall of its own as indicated at 19, and the pipe 20 extends up into the chamber above the drying tunnels and discharges through a series of heater flues 21 to 23, finally reaching the smoke pipe 24. At one end of the structure there is a casing 25 within which is mounted the fan 26 driven from a pulley 27 outside the main structure. The arrangement of the ceiling 16 is such that the fan discharges the air downwardly into the two drying tunnels, and at the opposite end of the tunnels it is drawn upwardly through a pair of openings in the ceiling 16 to be circulated over and under the smoke flues 21 to 23 to be re-heated.

The structure rests upon a suitable concrete

floor, or base, 28, and said floor also forms the support for the turn table 7. It will also be seen that there are two holes 30, 31, in the ceiling 16 where it extends over the furnace 18, the object being to allow a certain percent of fresh air to pass into the tunnels through the holes 19' and from the space surrounding the heater and be thereby heated while the doors 13 and 14 are allowed 5 to be open sufficiently to cause the discharge from the drier of sufficient air to carry away moisture. It will be seen that the side walls of the drier are spread slightly at 34, 35, the object being to allow the necessary space for 10 the turning of the cars on the turn table 7. The turn table 7 rests upon a series of rollers 40 and it is held in a central position by means of a pin 41, which pin also forms the pivot for a sprocket wheel 32. The sprocket 15 wheel 42 is engaged by sprocket chain 43 which chain is connected to the cable 44, 45, the latter passing around a take-up sheave 46, attached by means of a shackle 47, rod 48 and hand wheel 49, threaded on to rod 48 20 outside the structure of the drier. The sprocket chain passes around the sprocket wheel 42 and also around an idler 50. At the opposite end of the drier from the turn table the cables pass around the drums 51 25 and 52 respectively, each cable being wound around the drum in a reversible direction from the other so that as the shaft 53 which carries said drum is rotated, one cable will be unwound while the other one is wound 30 upon the drum. Under the turn table there are two stops 54 and 55, which stops are engaged by a heavy spring 56 on the upper side of the sprocket wheel 42, the arrangement being such that the sprocket wheel 35 will only turn the turn table in the direction indicated by the arrow, while said sprocket wheel is oscillating back and forth substantially 180°. It will also be seen that the sprocket wheel carries a lug 56 out of alignment 40 with the teeth of the wheel, which is capable of engaging either one of the two pivoted latches 57, 58, carried by the under side of the turn table. The latches 57, 58 are pivoted connected to the turn table and 45 each one has a spring as shown at 59, to hold said latches engaged with the stop 60 at the proper time, the cam 56 disengaging said latches when necessary. The said latches and a fixed stop 60 hold the turn table in the 50 proper position to align its tracks 61, to 64 with the tracks 5 and 6 that extend down the tunnel. A fixed stop 65 prevents the latch 57 from moving more than a fixed amount under the influence of its spring 59, there 55 being a similar stop for the latch 58. Since the cable 44 passes under its drum 51, and since those drums must, of course, be low enough to avoid interfering with the axles of the cars, the wheels of which are only 4" 60 in diameter, a roller 66 is provided to hold 65 the cable 44 up to the desired level. Adjacent the turn table there are two grooved rails 67, 68 for the support of a slide 69, which slide is connected to the cable by means of a clamp 70. This slide also has a latch 71 pivotally mounted thereon which is held in the raised position by means of a spiral spring 72, and the front end of the latch is so shaped that it will pass under the flange 73 of one of the cars, and enable that 75 car to be pulled off the turn table. Similarly there are two grooved rails 75, 76 which support a slide 77 carrying a spring hook 78 to push the line of incoming cars on to the turn table. The rotating of the shaft 53 is effected by means of a rack bar 79, which engages a pinion 80 on the end of the shaft 53, said shaft being supported in three suitable bearings 81, 82 and 83. The rack bar 80 85 is driven by means of a pitman 84 connected to a pin 85 on a worm wheel 86. The worm wheel 86 is driven from a small worm 87 on the motor shaft 88, said motor 89 being of any desired type. In order to prevent the cars from being pushed too far 90 ahead on the turn table, a stiff spring 90 is secured to the wall of the structure 91 and it is shaped to the same curve as the cars will take in traveling around with the turn table, 95 said spring being low enough to engage the cars as indicated by the dotted line at 90. 100 The operation of the apparatus is as follows: The tracks 67, 68 and 75, 76 are just as long as is required to move one car plus the length of the slides that operate in them. Assuming a car to be pushed into the drier on the track 5, it will be pushed in by hand until it can be caught by the hook 78, whereupon the motor 89 may be started and the drums 51, 52 will be operated to pull the car 105 ahead its own length. Other cars will be put into the drier on the track 5 until finally one car comes against the stiff spring 88, and this will stop the entire line of cars, but upon completion of each turn of the gear 86 the turn table 7 will be turned 180° bringing one of its latches 57 or 58 into contact with the stop 60, and as soon as a car has been brought to the position on the turn table shown in Figure 2 as vacant, the next 110 movement of the cables to bring the car into the drier on track 5 will take that particular car off the turn table on to track 6, and the operation will be repeated whenever it is desired to add another car to the drier. In the meantime, the air circulation by the fan will be drawn under and over the flue and then driven through the trays on the cars. All the time the doors 11 to 14 115 will be open much or little, as may be desired, to allow the escape of a certain amount of air from the drier, whereby the moisture is permitted to escape, and at the same time an equal amount of air is drawn through the openings 191 of the walls sur- 120 125

rounding the furnace 18, but of course no smoke whatever is permitted to escape from the furnace or from its smoke flues, into the drier.

5 Having thus described my invention, what I desire to secure by Letters Patent of the United States is as follows, but modifications may be made in carrying out the invention as shown in the drawings and in 10 the above particularly described form thereof, within the purview of the annexed claims.

I claim—

1. A drier of the class described, comprising a pair of tunnels side by side; means to move a line of cars into the drier through one of the tunnels, a turn table to receive the cars from said tunnel; means to turn said turn table 180° to place a car thereon 20 in front of the second tunnel; means to move a second line of cars out of the drier through the second tunnel; means to circulate the air through both of said tunnels toward the receiving end of the drier; means to heat 25 said air and means whereby a portion of the air circulated will be allowed to escape from the drier to remove the moisture from the materials being dried.

2. A drier of the class described, comprising a pair of tunnels side by side, doors at the inlet end of the drier, a turn table to receive cars from one of the tunnels and position them in front of the other tunnel; means to push a line of cars along one of the said 35 tunnels on to said turn table; means to prevent the car upon the turn table from being pushed too far; means to rotate the turn table to place the car thereon in front of the second tunnel, and means to move 40 that car, and a line of cars outwardly from the drier along said second tunnel.

3. A drier of the class described, comprising a pair of tunnels side by side, doors at the inlet end of the drier, a turn table at 45 the opposite end of said tunnels, cables for pulling a line of cars into the drier through one of the said tunnels and for turning the turn table to bring one of the cars placed thereon to a position in front of the second tunnel and other means on said table for removing that car from the turn table and pushing a line of cars into the second tunnel out of the drier, the movement being 50 carried out one car at a time.

55 4. A drier of the class described, comprising a pair of tunnels side by side, doors at the inlet end of the drier, means to take cars into the drier through one tunnel, and to remove the cars from the drier through 60 the other tunnel, a heater means to circulate the air through both of the tunnels in the same direction, a return flue containing heater flues over which the air is returned to the circulating means, and a chamber al-

lowing the heater open to the atmosphere 65 and to the heating chamber containing the flues whereby a percentage of fresh air may be drawn into the drier continuously.

5. A drier of the class described, comprising a pair of tunnels arranged side by side, doors at inlet end of the tunnels, means to move a series of cars into the drier through one of the tunnels, means to shift the cars from a position at the end of the inlet tunnel to a position at the end of the 75 exit tunnel, means to remove the cars from the drier through the exit tunnel, a fan to circulate the air in the same direction through both of said tunnels, and through a heating chamber over both of said tunnels, a 80 heating furnace at the side of the drier, and means whereby a certain percentage of air may be drawn into the heating chamber of the drier from a chamber surrounding said furnace to compensate for air escaping from 85 the drier charged with moisture.

6. A drier of the class described, comprising a pair of tunnels arranged side by side, with a heating chamber over both of said tunnels, a furnace, flues extending therefrom into the heating chamber, a smoke flue into which the smoke is finally discharged, doors at the inlet end of the drier for both tunnels, means to move a series of cars into the drier through one 90 tunnel and out of the same, through the other tunnel, and means to circulate the air in the drier through both of the tunnels, and through the heating chamber, so that the hottest air will pass over the cars at 95 an intermediate portion of the drying 100 operation.

7. A drier of the class described comprising a walled enclosure, two pairs of rails in said enclosure, trucks on said rails, fruit drying trays on said trucks, an entrance door in said enclosure for the trucks on one of said pair of rails, an exit door for the trucks on the other pair of said rails, a turn table at the inner end of said rails, two pairs 105 of rails on said turntable, a freely mounted sprocket-wheel on the under side of said turn table, a chain on said sprocket, a cable attached to one end of said chain and extending over an adjustable pulley to a winding 110 drum, a cable attached to the other end of said chain and extending to another winding drum, a common shaft for said drums, means to drive said shaft, one of said drums being adapted to wind up a cable while the 115 other is unwinding, means on said sprocket for turning said turntable in one direction, and means to stop said turntable with the rails in alignment.

In testimony whereof I have hereunto set 125 my hand this 27th day of October, A. D. 1925.

JOHN D. CANTONI.
